UNITED STATES PATENT OFFICE.

JOHN H. MURPHY, OF LOWELL, MASSACHUSETTS.

TOILET APPARATUS.

Application filed September 5, 1922. Serial No. 586,065.

To all whom it may concern:

Be it known that I, JOHN H. MURPHY, a citizen of the United States, residing at Lowell, in the county of Middlesex and State of Massachusetts, have invented certain new and useful Improvements in Toilet Apparatus; and I do hereby declare the following to be a full, clear, and exact description of the invention, such as will enable others skilled in the art to which it appertains to make and use the same.

The present invention relates to toilet apparatus and more particularly to toilet receptacles adapted to contain rouge, powder and similar preparations.

The object of the invention is to provide certain new and useful improvements in connection with what are technically known as compacts and more particularly to double compacts, which contain both rouge and powder or similar ingredients. These compacts comprise a container of suitable size and form and including in addition to rouge and powder one or more mirrors and puffs for the application of the rouge and powder. It is desirable that when the container is closed it shall present a compact and attractive exterior and when opened shall permit ready access to both the rouge and powder and permit inspection in the mirror. In addition, it is desirable that the mirror shall be protected when the container is closed in order to prevent breakage in the event that the container is dropped or brought into contact with an external object.

According to the present invention, the container consists essentially of two parts hinged together, each constituting a receptacle for rouge, powder or similar ingredients. Connected to the container and adapted to lie between the two parts when the container is closed is a mirror which may be readily moved into operative position when the two parts of the container are opened. In the simplest and most efficient form of the invention which has yet been devised, two flanged members of substantially similar shape are hinged together in such a manner that when open the two members forming the container may lie side by side in the same plane. A mirror is hinged to one of the members at a point removed from the hinge connection between the members and is adapted to be completely enclosed by the members when the container is shut and to be thrown back into a convenient position

when the container is open. With this construction, it will be evident that when the container is open both the rouge and powder are accessible and may be used as desired without the necessity of manipulating the container or the mirror.

Still further features of the invention consist in certain novel features of construction, combinations and arrangements of parts hereinafter described and claimed, the advantages of which will be obvious to those skilled in the art from the following description.

In the accompanying drawings illustrating the preferred form of the invention Fig. 1 represents a perspective view of the container with the two parts opened and the mirror thrown back; Fig. 2 is a section of the container upon the line 2—2 of Fig. 1; Fig. 3 is a section of the container upon the line 3—3 of Fig. 1; and Fig. 4 is a section of the container when closed.

According to the illustrated embodiment of the invention, the container comprises cooperating members 10 and 11 which are hinged together at 13 to permit the container to be closed, as indicated at Fig. 4, or opened, as indicated in Fig. 2. The member 10 as shown is provided with an annular shoulder 14 upon the exterior surface, which forms a seat for the flange of the member 11 and causes the container to present a finished, unbroken exterior when closed. The receptacle formed by the member 10 contains a cake of rouge, indicated at 16, which may be conveniently retained in place by a ring 18 having an inner lip 20 which bears upon the rouge cake and an outer flange 22 which fits closely within the member 10. The receptacle constituted by the member 11 contains a larger cake of powder 24, which is retained in place by a ring 26 having an inturned flange 28. It will be observed that the inner dimensions of the receptacles are the same and that either one may be employed for holding the rouge or powder by simply employing the proper sealing ring. A single mirror 30 is hinged at 32 to the member 10, the hinge 32 being so located with respect to the hinge 13 that when the container is open, as indicated in Fig. 1, the mirror will lie in the plane of the receptacles and occupy a position substantially between the receptacles.

When the container is closed, the mirror may be swung about the hinge connection

into the member 10, as shown in Fig. 4, this movement being limited by a lug 34 projecting from the inner wall of the member. The cooperating member 11 may then 5 be closed with the mirror in position between the two members, as clearly indicated. In this position, the face and back of the mirror are retained out of contact with the remaining portions of the container, thus 10 minimizing the liability of breaking the mirror. As shown in the drawings, the mirror conveniently comprises a back 40 of metal or other suitable material, enclosing and surrounding the edge of the reflecting 15 portion of the mirror and a projecting knob 42 by virtue of which the mirror may be drawn back into operative position when the container is opened. It is desirable that puffs for the application of the rouge and 20 powder shall be contained within the compact and it will be observed from Fig. 4 that there is ample space between the opposite sides of the mirror and the rouge and powder cakes for the reception of flat puffs, such 25 as indicated at 44 and 46.

It will be evident that this form of container presents a compact and attractive exterior when not in use and when open provides a compact and readily available unit 30 which may be easily retained in the palm of one hand, leaving the other hand free for the application of the rouge and powder. Furthermore, the opening of the container makes both the rouge and powder accessible 35 at one and the same time and permits the single mirror to be utilized in applying either the rouge or powder or both. It will be furthermore obvious that with the unit open, as indicated in Fig. 1, the mirror 40 may be readily tipped to any desired angle or inclination in accordance with the needs of the user.

It will be obvious to those skilled in the art that the compact as a whole may be constructed of metal or of celluloid and similar materials, in accordance with the requirements of the trade.

While it is preferred to employ the specific construction and arrangement of parts 50 shown and described, it will be understood

that this construction and arrangement is not essential except so far as specified in the claims and may be changed or modified without departing from the broader features of the invention. 55

The invention having been described, what is claimed is:

1. A toilet receptacle comprising two members hinged together and each adapted to contain powder or similar toilet ingredients, and a mirror hinged to one of the members at a point offset from the hinged connection between the members to swing at an angle to the swing of the other of said members and to be thrown back substantially 60 in the plane of the members when the receptacle is open and to be closed over the toilet ingredient in the member to which it is hinged. 65

2. A toilet apparatus comprising two cup shaped members hinged together and adapted to contain powder or similar ingredients, a mirror connected with the members and adapted to lie therebetween when the container is closed, and a slip ring having 70 an inturned flange adapted to engage with the cake of powder or ingredient and an outer peripheral flange fitting closely within the cup shaped member, the ring being adapted to retain the cake of ingredient 75 in place within the member and to permit access thereto. 80

3. In combination, a container having a cover and a cosmetic block having an oval upper face arranged in said container, and a guard plate formed with a central opening projecting inwardly of said container and having its inner peripheral edge bent downwardly to engage and center said cosmetic block. 85

4. A vanity case comprising a body member for receiving a toilet compact, a lid member hinged to said body having means for receiving and retaining a toilet compact, and a mirror plate hinged to one of said members to swing at an angle to the swing of the other of said members and to be closed over the toilet compact in the member to which it is hinged. 90 95

JOHN H. MURPHY.
